Thomas H. C. Beall,
BY
Chester Bradford,
ATTORNEY.

UNITED STATES PATENT OFFICE.

THOMAS H. C. BEALL, OF CICERO, INDIANA.

HEATER FOR VEHICLES.

SPECIFICATION forming part of Letters Patent No. 554,106, dated February 4, 1896.

Application filed May 28, 1895. Serial No. 550,957. (No model.)

To all whom it may concern.

Be it known that I, THOMAS H. C. BEALL, a citizen of the United States, residing at Cicero, in the county of Hamilton and State 5 of Indiana, have invented certain new and useful Improvements in Heaters for Vehicles, of which the following is a specification.

The object of my said invention is to provide a convenient and efficient means where- 10 by occupants of vehicles may be continuously and uniformly kept warm, said invention being designed to supersede what are ordinarily denominated "foot-warmers."

This invention consists in a specially de- 15 signed and constructed receptacle, secured below the floor of the vehicle, and containing a heater also specially designed and constructed for the purpose, all as will be hereinafter more particularly described and 20 claimed.

Referring to the accompanying drawings, which are made a part hereof, and on which similar letters of reference indicate similar parts, Figure 1 is a perspective view of a vehicle 25 provided with a heater embodying my said invention; Fig. 2, a detail vertical sectional view through the heater and the immediately adjacent portions of the floor of the vehicle on the dotted lines 2 2 in Figs. 3 and 4; Fig. 30 3, a horizontal sectional view looking downwardly from the dotted line 3 3 in Fig. 2, and Fig. 4 a horizontal sectional view looking downwardly from the dotted line 4 4 in Fig. 2.

In said drawings the portions marked A 35 represent the vehicle structure, particularly the floor thereof; B, the receptacle for or outer casing of my improved heater; C, the heater proper; D, a spring-catch or spring-catches by which said heater or "lamp" is 40 held firmly to its seat; E, a flue leading upwardly from the heater by which the products of combustion are guided in operation, and F spring-catches by which the flue and its deflecting-plate are held in place.

The vehicle itself may be of any ordinary 45 or desired construction and needs no special description. It may, of course, be either a wheeled vehicle, as shown, or a sleigh or other vehicle on runners. It may be provided with 50 one or more of my improved heaters, as may be desired. One will usually be found suffi-

cient; but some may prefer two smaller ones, one at or near each side of the vehicle. The floor A is cut away at the point where the heater is attached underneath and a door A' 55 provided, which, as shown in Fig. 2, is preferably hinged at one side, as at a, and contains numerous small perforations through which the heat may pass up into the portion of the vehicle occupied by the persons riding 60 therein. Such persons being commonly covered with robes or blankets, the space in which are their lower extremities is thus inclosed, and, as the heat is discharged directly into this space, they are thus kept warm and com- 65 fortable even in the coldest and most inclement weather. The heater being constantly in operation, the warmth is caused to be continuously the same, instead of, as with ordinary foot-warmers, being dissipated 70 in a short time.

The receptacle or casing B is usually formed of sheet metal, preferably substantially in the form shown in Fig. 2, although, of course, the form may be changed, if desired, and is 75 secured to the under side of the floor A of the vehicle by screws, rivets, or otherwise and contains the heating apparatus. Its lower end is open to receive the body of the heater proper, C, as shown. This permits the lower 80 side of said heater to project out into the open air, and it is thus itself kept cool, and danger of overheating the oil therein is thus avoided. The extreme lower edge of the casing B terminates in a flange b, upon which a 85 corresponding flange c on the body of the heater C will rest, as shown.

The heater proper, C, is in the form, generally speaking, of a metal lamp, having a burner on its upper side similar to a common 90 form of lamp, and is adapted to use oil for a fuel. As above stated, it is preferably provided with a surrounding flange c, which rests upon the flange b in the bottom of the casing B, and thus said heater or lamp is firmly sup- 95 ported, being inserted into the casing from the top after raising the door A'. This heater or lamp is intended to be quite capacious, so as to contain a quantity of oil sufficient to last for several hours, or during any ordinary single use of the vehicle.

The spring D is preferably a double spring,

as shown, although two single springs might be used, if desired, or a different form substituted. It is preferably formed of wire and hinged, at *d*, at one side, and adapted to engage with projections *b'* on the inner surface of the casing *B* at the other. It is so proportioned and arranged as to bear forcibly on the top of the body of the heater proper, *C*, and thus hold it firmly into place. Being preferably round it will spring in either direction and thus may spring sidewise to pass below the projections *b'* as well as downwardly.

The flue *E* is in itself generally formed similar to a lamp-chimney (as the heater *C* is in itself generally formed similar to a lamp) and occupies the same relation to said heater as a chimney does to a lamp. It is, however, constructed of sheet metal, and has a plate *E'* of considerable diameter secured to its upper end, with radial perforations extending out laterally through the sides of said flue below said plate. The plate, as shown, occupies the greater portion, transversely, of the interior of the casing *B*, there being an annular space around said plate at the outer edge, and preferably rests mainly on brackets *b*² on the inside of the casing *B*, although it may rest altogether on the burner, instead of partially thereon, as shown. Its arrangement secures that the heat which arises from the burner shall be deflected from its upward course and pass out through the radial perforations mentioned below the deflecting-plate, thence to the edge and up through the annular space, and thence through the perforations in the cover *A'*, which forms a part of the floor of the vehicle, as above stated. Of course a portion of the heat will be radiated from the upper surface of said deflecting-plate, and this, together with the arrangement just described, secures a substantially even distribution of the heat throughout the entire upper portion of the chamber formed by the casing *B*, instead of, as would otherwise be the case, having said heat concentrated at a single point. This distribution of the heat is of much consequence, as the amount of heat generated, if allowed to rise directly from the burner, would heat the floor entirely too hot for comfort and would likely be the occasion of burning whatever came in contact therewith, even if the door *A'* were itself, as I prefer, made of or lined with metal.

The flue and deflecting-plate may be held firmly into place by any desired means. I have shown spring-catches *F* secured to the sides of the casing *B* by rivets *f* at points between the brackets *b*² and engaging with the edges of said plate *E'*, said spring-catches being bent to a wedge-shaped formation at the

point of engagement, so as to press downwardly as well as sidewise on said plate.

The device as a whole is simple and inexpensive in construction, is perfectly safe in use, and, as will be readily understood, a great convenience and comfort to such persons as have occasion to drive in cold and inclement weather, particularly to physicians and others whose duties call them constantly from home.

Having thus fully described my said invention, what I claim as new, and desire to secure by Letters Patent, is—

1. The combination, in a heating device for vehicles, of a casing secured to the under side of the floor of the vehicle, a heater proper mounted in the lower portion of said casing and supported by a flange thereon on a flange on said casing, and a two-part spring-bar hinged at one end to one side of said casing and adapted to engage at its other end with a catch on the opposite side of said casing, one of its parts passing on each side of the flue of said heater and formed to bear, when closed down, firmly upon the top thereof, whereby said heater is firmly but removably held to its seat, substantially as set forth.

2. The combination in a heating device for vehicles, of a casing, a heater proper secured therein, a flue extending upwardly from the burner of said heater, a deflecting-plate extending across and secured to the top of said flue, which is provided with perforations in its sides under said deflecting-plate, and spring-catches which engage with the deflecting-plate, whereby said flue is firmly but removably held in place, substantially as set forth.

3. The combination, in a heating device for vehicles, of the outer casing secured to the under side of the floor of the vehicle, a perforated cover over the space inclosed by said casing, a lamp or heater proper mounted in the bottom of said casing, spring-catches whereby said lamp or heater is held firmly, a flue or chimney on said lamp or heater, a deflecting-plate secured on the upper end of said flue or chimney, which flue or chimney has radial perforations below said deflecting-plate, supporting brackets on the interior surface of said casing for said deflecting-plate, and spring-catches secured to said interior casing and engaging with and holding said deflecting-plate onto said brackets, the whole being constructed, arranged and operating as and for the purpose set forth.

In witness whereof I have hereunto set my hand and seal, at Indianapolis, Indiana, this 22d day of May, A. D. 1895.

THOMAS H. C. BEALL. [L. S.]
